CLAIM

The ornamental design for a smart watch with earbuds, as shown and described.

DESCRIPTION

FIG. 1 is a front elevation view of a smart watch with earbuds showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is an enlarged view of the encircled portion 9 in FIG. 7;

FIG. 10 is an enlarged view of the encircled portion 10 in FIG. 8;

FIG. 11 is a front elevation view of the earbuds portion of the smart watch with earbuds shown separately to show aspects of the design that are not visible when combined;

FIG. 12 is a back elevation view thereof;

FIG. 13 is a left-side view thereof;

FIG. 14 is a right-side view thereof;

FIG. 15 is a top plan view thereof;

FIG. 16 is a bottom plan view thereof;

FIG. 17 is a perspective view thereof;

FIG. 18 is another perspective view thereof; and,

FIG. 19 is an exploded perspective view of the smart watch with earbuds.

The broken lines depict portions of the smart watch with earbuds that form no part of the claimed design.

The dash-dot lines in FIGS. 7, 8, 9, and 10 illustrate the enlarged view indicators and form no part of the claimed design.

1 Claim, 19 Drawing Sheets
